UNITED STATES PATENT OFFICE.

STEPHEN H. HEAD, OF BOSTON, MASSACHUSETTS, ASSIGNOR TO HIMSELF AND WM. P. PARROTT, OF SAME PLACE.

STEAM-BOILER.

Specification of Letters Patent No. 26,002, dated November 1, 1859.

To all whom it may concern:

Be it known that I, STEPHEN H. HEAD, of Boston, in the county of Suffolk and State of Massachusetts, have invented certain Improvements in Steam-Boilers, of which the following is a full, clear, and exact description, reference being had to the accompanying drawings, making part of this specification, in which—

10 Figure 1 is a perspective view of a boiler; Fig. 2 a longitudinal vertical section of the same; Fig. 3 a transverse vertical section through the middle of the furnace.

Boilers have been constructed with double 15 furnaces where the combustion chamber was placed above the furnaces, the bottom of the chamber being formed of a horizontal water partition through openings in which the products of combustion passed from one or 20 other of the furnaces, but the position of this chamber was detrimental to the rapid generation of steam in that part of the boiler immediately over the furnaces, on account of the horizontal water partition being in- 25 terposed between the body of the fire in the furnaces and the crown sheet, while the steam formed in this water partition was compelled to traverse a considerable space horizontally before it could mingle with that 30 in the body of the boiler. These difficulties have been overcome by my improved arrangement of placing the combustion chamber immediately in front of the furnaces, which allowed the fire in the furnaces to rise 35 directly against the crown sheet; and allows the steam generated in the partition D to rise freely and vertically into the boiler. This arrangement of the combustion chamber also enables me to place the flue which 40 connected the two furnaces, at the back of the furnaces so that the flame from one furnace as it passes to the other will impinge directly on the rear plate of the fire box which is generally the coolest and most diffi- 45 cult to heat. Boilers have also been constructed with two furnaces having a lateral passage to connect one furnace with the other, and the application of dampers to compel the smoke to pass from one furnace 50 over the incandescent fuel of the other, and thus promote combustion of the volatile gases. But this arrangement could not be applied advantageously to tubular boilers, because when one of the furnaces was shut 55 off, all the products of combustion must pass

through one half of the flues the other half being closed by the closed damper, and consequently would be inapplicable to locomotive boilers. By my arrangement of a chamber in front of the two furnaces, which is 60 common to both the furnaces in whatever position the damper may be the products of combustion though coming from one furnace only, passes through all the tubes or flues alike, because the dampers only change 65 the line of draft through the furnaces, but do not prevent the products of combustion from taking the entire series of flues or tubes, after they have passed through the furnace. Besides this chamber in front of the furnaces, 70 serves as a space through which a single damper that may shut off either furnace, or leave both open, can freely swing; and is moreover a combustion chamber. This chamber at the front of the furnaces, 75 and its objects and purposes in connection with the two furnaces and the lateral passage between them, is what constitutes the novel and useful feature of my invention.

To enable others skilled in the art to understand and use my invention I will proceed to describe the manner in which I have carried it out.

In the said drawings A is the boiler, B and C fire spaces or furnaces which are separated by the water space or partition D, and are fed alternately by fuel introduced through the doors b, c. This partition D does not extend to the back of the furnace or that part in which the doors b, c, are placed but leaves a space or flue E of the whole height of the furnaces, the water in this partition is in communication with that in the boiler, though the upper part of the partition which is open, and also with that in the 90 water space d at the front of the furnaces.

A chamber F extends from the front of the two furnaces B and C and is in communication with them both, the passage from either furnace being commanded by a valve or damper f, which is pivoted on a rod e immediately in front of the partition D, (for the convenience of turning this rod it may extend up through the top of the boiler in a tube g, as shown in Figs. 2 and 3.) The front of the chamber F forms the flue or tube plate in which the boiler flues or tubes are inserted. The products of combustion coming from either one of the furnaces, enters the chamber F, and what is not con- 100 105 110

sumed there by ignition, as well as the heat and flame, is free to take the entire series of flues which connect with said chamber—and thus this system of furnaces may be made available for locomotive boilers, and with great advantage.

The following will be the operation of my improved arrangement of furnaces: When it becomes necessary to replenish one of the furnaces with fuel (for example furnace C) the damper *f* is turned so as to shut off the communication between this furnace and the chamber F; the course of the smoke and gases from this fire will then be toward the back of the furnace as indicated by the arrow Fig. 2, through the flue E, and over the fire in the furnace B, traversing the entire length of this furnace and being there consumed or nearly all consumed before they reach the chamber F. When the other furnace is to be fed, the damper is turned to the other side, and the current is reversed, or sent over the fire in the furnace C'. When both fires are in full operation and consequently not giving off much smoke, the

damper *f* may be set in a straight line behind the partition D by which it will be in a measure protected from the full power of the flame.

The chamber F, besides giving space for 30 turning the damper *f*, also serves as a combustion chamber where the gases from the fires which have not been previously consumed are here mingled and burned before entering the flues or tubes and the heat is 35 free to take the entire series of flues, not being controlled in any degree by the damper.

What I claim as my invention and desire to secure by Letters Patent is—

In combination with the furnaces B, C, and the lateral passage E, and damper *e*, the chamber F located at the front of the furnaces and between them and the flues, for the purpose and in the manner substantially 45 as herein set forth.

STEPHEN H. HEAD.
